RAY P. JACKSON, OF EDGEWOOD PARK, PENNSYLVANIA, ASSIGNOR TO WESTINGHOUSE ELECTRIC & MANUFACTURING COMPANY, A CORPORATION OF PENNSYLVANIA.

INSULATOR.

Application filed October 2, 1922. Serial No. 591,736.

My invention relates to insulators and particularly to suspension insulators adapted for service in connection with high-voltage power circuits.

5 One object of my invention is to provide an insulator of the above-indicated character having an increased amount of creepage surface that is exposed to a direct washing action by rain, relative to similar insulators of the prior art.

Another object of my invention is to provide an insulator of refractory insulating material that shall be so constructed as to have a maximum surface area for given 15 weight.

A further object of my invention is to provide a high-voltage suspension insulator that shall be simple and durable in construction, economical to manufacture and 20 effective in its operation.

In the development of high-potential insulators, various factors were introduced as the commercial voltages of power circuits were increased. In the earlier high-voltage 25 systems, which are considered low-voltage systems, as compared with systems now in use and contemplated, the principal considerations were sufficient mechanical strength and thickness of insulation. After 30 these considerations, came the feature of creepage surface which has been modified and extended in various ways. Later, the idea of keeping arcs away from the insulating members was conceived and was put into 35 practice in the form of arcing rings and horns. With the advent of still greater commercial power-circuit voltages, the continued endeavor toward improvement resulted in the suggestion of having the insulating bodies shaped to conform as nearly 40 as practicable to the electrostatic fields and, further, to so distribute the fields as to avoid concentration thereof.

The fact that deposits of dust and other 45 foreign matter on insulators reduced the insulating properties thereof and caused breakdown at voltages below those at which clean insulators break down was recognized for a considerable time before the idea of 50 providing the insulators with surfaces that could be washed by rain was suggested.

This feature of providing what has been termed "washed surfaces" is a comparatively recent development in the high-potential

insulator art and, so far as developed, has 55 been an appreciable improvement.

It is my aim to further the development of "washed-surface" insulators by providing an insulator of that general type but of entirely different form so that the washing action is 60 more nearly effected over the entire exposed surface thereof.

In practicing my invention, I provide an insulator, similar to certain suspension insulators of the cap-and-pin type, in which 65 the surface creepage or petticoat portion, instead of merely extending to an outer limiting position and ending there, is continued inwardly from near that position in such manner as to provide additional creepage 70 surface, in which the greater portion of the creepage surface is subject to a direct washing action by rain.

The insulator is, further, so shaped and proportioned, and is so constructed of substantially uniform thickness throughout, as to obtain a substantially maximum surface area for a given weight of the material of which it is composed.

The single figure of the accompanying 80 drawing is a side view, partially in elevation and partially in section, of an insulator embodying my invention.

The insulator comprises, in general, a main insulating body member 1, an auxiliary insulating member 2 within the member 1, a metal-cap terminal member 3 and a pin or tension member 4 for attachment, by a pin 5, to the next adjacent similar insulator or other device.

The main insulating body member 1 is provided with an end portion 6 of inverted substantially cup shape, over which the member 3 is secured in position, as by cementing. From the open end or perimeter 95 of the cup-shaped portion 6, an annular portion 7, similar to an ordinary petticoat member, projects, laterally and longitudinally to an outer limiting portion 8.

An annular portion 9 joins the portion 7 100 adjacent to the portion 8 and converges therefrom to a portion 10 at one end thereof. This construction provides a hollow refractory member having a bulging portion which, in ordinary insulators of a similar 105 type, is solid or filled.

The portions 7 and 9 are of substantially frusto-conical shape but slightly curved to

conform to equipotential and flow-line surfaces, respectively, in accordance with certain prior art. Washing will take place over the entire surface of the portion 7, and over 5 the greater surface of the portion 9, by direct impact of rain. Thus, nearly all of the outer exposed surface of the insulator will be subject to washing, while the inner surface, by reason of the constricted mouth of 10 the member 1, will be protected against undue deposits of dust and other foreign matter. Since the member 1 has substantially uniform relatively thin walls, the auxiliary insulating member 2, which may be cemented 15 in position in the cup-shaped portion 6, may be added to provide sufficient insulation, for certain voltages, at the head of the insulator, between the members 3 and 4.

The pin or tension member 4 is provided, 20 at one end, with an enlarged or anchor portion 12 for mounting, as by cementing, in the member 2 or in the portion 6 and, at its other end, with an attachment portion for the reception of the pin 5 and the next adjacent insulator.

While in certain localities, the usual insulator becomes very dirty, or deposited with 25 dust, and is thereby rendered inefficient, an insulator constructed in accordance with my invention will be periodically cleaned and, in 30 general, be maintained at a much higher state of efficiency from this cause than insulators of the prior art.

Further, by reason of the particular construction and the uniformity of thickness of 35 the walls of the member 1, the latter, not only provides a substantially maximum surface area for a given weight, but facilitates its construction in porcelain. In other 40 words, the difficulties attending the firing of uneven masses of refractory material are removed and an insulator of uniform quality is obtained.

While I have shown and described a particular form of my invention, various 45 changes and modifications may be made therein without departing from the spirit and scope thereof and I desire, therefore, that only such limitations shall be imposed 50 as are set forth in the appended claims.

I claim as my invention:

1. An insulator comprising an insulating member including a head, a portion having an annular water-shed surface diverging

from the lower end of the head and a lower 55 portion having an annular creepage surface of relatively great length and area sloping inwardly and downwardly from a position closely adjacent to the outer perimeter of said water-shed surface in such position as 60 to receive driving rain directly, said water-shed surface portion projecting only slightly beyond the upper end of said lower portion to provide a water-drip portion preventing the passage of a continuous stream 65 of water along the water-shed and creepage surfaces but permitting the washing of the major portion of said creepage surface by driving rains.

2. An insulator comprising an insulating 70 member including a head, a portion having an annular water-shed surface sloping outwardly and downwardly from the lower end of the head and a lower portion having an annular creepage-surface of relatively great 75 length and area sloping inwardly and downwardly from a position closely adjacent to the outer perimeter of said water-shed surface, said water-shed surface portion projecting only slightly beyond the upper end 80 of said lower portion to provide a water-drip portion preventing the formation of a continuous stream of water along the water-shed and creepage surfaces but permitting the major portion of said creepage surface 85 to be washed by driving rains.

3. An insulator comprising an insulating body having a head portion, an annular surface-creepage water-shed portion sloping downwardly and outwardly from the lower 90 end of said head portion and an annular surface-creepage flange of relatively great length and area sloping downwardly and inwardly from a position closely adjacent to the outer perimeter of said water-shed portion, said water-shed portion projecting only slightly beyond the upper end of said 95 flange and constituting a water-drip portion to prevent the passage of a continuous water stream along the water shed and the outer 100 surface of the flange but permitting the washing of the major portion of said outer surface by driving rains.

In testimony whereof, I have hereunto 105 subscribed my name this 27th day of September 1922.

RAY P. JACKSON.
